CLAIM

The ornamental design for furniture, as shown and described.

DESCRIPTION

FIG. 1 is a left side perspective view of a case good item of furniture showing my new design, and the right side perspective view is a mirror image;

FIG. 2 is a left side elevation view of the item of FIG. 1 and the right side elevation view is a mirror image;

FIG. 3 is a front elevation view of the item of FIG. 1;

FIG. 4 is a top plan view of the item of FIG. 1; and,

FIG. 5 is an enlarged perspective view of one of the legs shown in FIGS. 1 to 4, shown separately for clarity of disclosure.

In each item shown in FIGS. 1 to 4, the front face surface portion is uniformly concave.
